WILLARD BYRON CAMPBELL, OF JACKSON, MICHIGAN.

ADJUSTABLE SICK-BED CUSPIDOR.

No. 829,059.

Specification of Letters Patent.

Patented Aug. 21, 1906.

Application filed October 10, 1904. Serial No. 227,905.

To all whom it may concern:

Be it known that I, WILLARD BYRON CAMPBELL, a citizen of the United States, residing at Jackson, in the county of Jackson and State of Michigan, have invented certain new and useful Improvements in Adjustable Sick-Bed Cuspidors; and I do hereby declare the following to be a full, clear, and exact description of the invention, such as will enable others skilled in the art to which it appertains to make and use the same.

This invention is designed for use by invalids, either in hospitals or private homes, as well as by dentists' patients and other disabled persons who are confined to beds or chairs and unable to readily avail themselves of the ordinary cuspidors.

The device, as illustrated herein, consists principally of a cuspidor or spittoon adjustably supported by tubular connections from a base or stand having a receptacle for holding the patient's discharges, though I am not limited to this location of the receiver for the discharges, the base merely affording a convenient inclosure for the same.

The principal objects of the invention are to provide for practically universal and ready adjustment of the cuspidor, so that it can be easily arranged by the patient himself in most convenient position for use; to render the connections and joints of the tubular supporting-standard such as to permit easy adjustment and extension, yet stiff enough to support the cuspidor in any position without need of fastenings or props, and also practically water-tight so as to prevent leakage or emission of saliva at the joints, and to insure cleanliness and sanitation by draining off the patient's expectorations and discharges, shutting off or trapping the collected discharges from the cuspidor, and also avoiding leakage of saliva at the pipe-joints or elsewhere.

In the accompanying drawings, which form a part of this specification, I have illustrated a convenient and efficient apparatus embodying my invention, which, however, is susceptible of other embodiments and various modifications.

Without limiting myself, therefore, to the specific construction shown the invention will be fully described with reference to said drawings and thereafter defined in the claims following the description.

Figure 1 is a rear elevation of the device

shown in perfectly upright position. Fig. 2 is a central vertical section of the same, taken on line 2 2 of Fig. 1 looking in the direction of the arrow. Fig. 3 is an enlarged sectional view of one of the hinged pipe-joints, showing the adjacent pipe-sections in alinement. Fig. 4 is a similar view of said joint, showing one pipe-section turned at an angle and in such position as to shut off communication between the two pipe-sections. Fig. 5 is a side elevation of the device, shown with its tubular supporting-standard adjusted at an angular position and holding the cuspidor not directly over the base. Fig. 6 is a central vertical section of the device in this same position. Fig. 7 is an enlarged detail, comprising a cross-section on line 7 7 of Fig. 5 looking in the direction of the arrow and parts behind said line in elevation. Fig. 8 is an enlarged side view of one of the hinged pipe-joints with part broken away and part in section. Fig. 9 is a detail top plan view of a ring for holding the base. Fig. 10 is a detail view of one of the connections between said ring and base, showing these parts disconnected.

Referring to the drawings, *a* denotes the base of the device, which is a hollow receptacle, in this instance dome-shaped, with a comparatively large bottom to furnish a stable support. Rising from this base-receptacle is the tubular supporting-standard *b*, comprising a plurality of telescopically-arranged tubes or pipe-sections, with suitably-interposed joints to permit angular adjustment. This standard carries at its upper end the cuspidor or spittoon *c*, from which the patient's expectorations and discharges are conducted through the tubular standard to the base-receptacle or into a vessel or reservoir *d*, placed therein or into whatever receiver the conduit may discharge.

The base-receptacle *a* may be constructed to serve itself as the reservoir for accumulated discharges from the cuspidor *c*; but for this purpose there is preferably provided a separate removable holder or reservoir *d*, which may be an ordinary cuspidor or any suitable vessel. The base may be formed with an open bottom to permit lifting the whole apparatus above the vessel *d*, or, if preferred, it may have a closed bottom and a removable door or plate, as at *e*. In the present illustration in addition to the removable plate *e* the base has an open bottom and

rests on internal lugs f' in a supporting-ring f , which has external lugs to receive screws g for fastening it to the floor. (See Figs. 9 and 10.) The bottom of the base has lugs a' , which when the base is set into its ring fall into suitably-disposed notches f^2 thereof, and then on turning the base its said lugs a' pass into slots f^3 , extending from said notches, while spring-lifted catches f^4 rise up and lock the lugs a' in place. In Fig. 10 the catch f^4 is shown depressed, as it would be when the lug a' is let down into the notch f^2 . Said catches f^4 are provided with knobs f^5 to depress them when it is desired to disconnect and lift the base out of its ring. One spring-catch f^4 may be preferable for allowing convenient detachment of the dome by a single individual.

In use by a bedside the device is set as closely to the bed as possible, usually with the lower part of the standard b beside the bed-rail and with the rear half of the base and its fastening-screws under the bed out of the way. To further insure rigidity and stability of the device, any suitable wire, clamp, or fastening may be used for holding the standard b firmly to the bed-rail, wherefore the lowest section of said standard is shown provided with a hook h for engagement by the wire or other device employed for that purpose, serving also as a handle. The standard b , as aforesaid, comprises a plurality of telescopically-arranged tubes or pipe-sections with suitably-interposed joints to permit angular adjustment, preferably two of such joints, as indicated by the letter l in the drawings, one between the upper part of the standard and the cuspidor c , the other medially disposed and dividing the standard into two parts or sections, of which the upper one is angularly adjustable with respect to the lower vertical section. In the present illustration the said lower section comprises three telescopically-arranged tubes j , the outer one of which is shown having its lower end fitted in a short tube or neck i in the top of the base-receptacle, while the said upper section comprises two of such telescopically-arranged tubes k . The invention is, however, not confined to any particular number of tubes either for the standard as a whole or for either section. The tubes are closely fitted one within another, so as to permit adjustment and yet remain in any extended or adjusted position. It will be noted that each telescopic tube is arranged within the next lower tube, so that the fluid discharged from the cuspidor will flow past the inner joints and cannot ooze between the interfitting portions of the tubes. By virtue of this arrangement, especially of the three lower tubes j , there is also provided a large range for extension of the standard, while yet the upper section, with its cuspidor c , can be lowered to a proper degree for low

beds or for use of a person sitting or reclining in a chair. The lowering or collapsing of the tubes may be limited by suitable beads or collars formed on their upper ends, as shown, to insure against accidentally pushing a tube down out of reach. 70

An important feature of this invention resides in the joints l , which constitute stiff hinges or elbow-joints permitting angular adjustments of the upper section and cuspidor, while preventing escape or oozing out of fluid at such joints. As both joints are substantially similar, a detailed description of the lower one or that connecting the two sections of the tubular standard will suffice. 75

As shown more clearly in Figs. 3 and 4, the upper end of the uppermost pipe j is rigidly jointed to a transverse cylinder or casing m at a bottom opening thereof, and the lower end of the adjacent tube k is inserted clear through and affixed rigidly in a similarly-disposed cylinder n , which is fitted tight within the outer cylinder or m , but is susceptible of being turned therein, thus providing trunnions for the upper section of the standard, said outer cylinder m having a peripheral cross-slot, as indicated at o , to accommodate said tube k when the upper section of the standard is tilted. Preferably the contiguous ends of said tubes j and k are of like size and are flush with the interior of casing or cylinder m , so that said ends contact and exactly register when the tubes are in alignment. The tubes will also register to a lesser extent when the upper section of the standard is slightly tilted; but when said upper section is tilted at a greater angle not far from the vertical the lower end of the tube k is moved opposite the interior of the casing m , and thus communication is entirely shut off between the upper and lower sections of the conduit. Since the upper joint between the cuspidor c and upper section of the standard is similar, it is obvious that either joint may serve as a trap to shut off and confine the discharges and vapors in the base-receptacle or its inclosed vessel d by tilting the cuspidor with respect to the upper section or by adjusting the upper section with respect to the lower section. In Figs. 5 and 6 both joints are shown in such position as to act as traps. 100 With reference to the upper joint particularly it may be mentioned that the cuspidor c may be either mounted on a tube inserted through the inner cylinder n of that joint or its bottom may be formed with a tubular extension p , inserted through said cylinder, to communicate with the uppermost tube k , as shown. It will be understood that all modifications—such as a reversal of the relations of the parts m and n or formation of the inner cylinder n with closed ends and with the tube k or p not inserted clear through, but merely protruding thereinto, or any departure from 105 110 115 120 125

the mechanical nicety herein set forth—are embraced within the scope of this invention, though the present construction is preferred for its excellence and efficiency. With these joints *l* it is unnecessary to close the ends of the cylinders *m* and *n*; but the ends of the outer cylinders *m* are nevertheless shown provided with removable caps *q*, which enhance the ornamental appearance of the apparatus and also serve as supports for spring-pressed studs or catches *r*, which catches enter through a hole in the end of the outer cylinder *m* and engage one of a series of apertures or perforations in the inner cylinder *n*, Fig. 8, for the purpose of absolutely insuring the maintenance of the tubing in any position to which it may be adjusted. The catch *r* may be raised by the fingers to disengage the apertures or perforations in the inner cylinder *n* when it is desired to adjust the tubing angularly. As before stated, the joints are stiff enough to hold the cuspidor in different positions of their own accord, owing to the tight fit of the trunnions *n* in the bearings *m*; but it may be desirable to employ some suitable catches, such as *r*, to render this effect absolute at all times, as in the case of wear of the joints, and to further increase the efficiency of the apparatus. A similar catch *s* is shown for locking the two tubes *k* of the upper section in fixed relation, said catch being entered through a shoulder or projection on the lower one of said tubes and engaging any one of an annular series of apertures or perforations in a flange or projection on the upper tube, as shown more clearly in Fig. 7, where the full lines show the upper tube with its cuspidor in such relative position to the lower tube, as in Fig. 5, while the dotted lines indicate the cuspidor turned at an angle with the center of tubes *k* as an axis.

In Figs. 5 and 6 the upper section of the standard *b* is shown adjusted or tilted over to approximately horizontal position, and the cuspidor tilted up to practically vertical position. Now it is obvious that the whole upper section with the cuspidor may not only be raised to different heights by extending the telescopically-arranged tubes *j*, but may also be swung around to any desired position, turning on the axes of said tubes *j*, while it may also be adjusted or tilted to different angular positions on the lower hinge *l*. Likewise the cuspidors may be tilted or turned on its hinge *l*, or together with its said hinge may be turned about the axes of tubes *k*, as indicated by dotted lines in Fig. 7. The upper section of the standard may also be lengthened, if desired, by extending the tubes *k*, though this is usually unnecessary, because the extension afforded by the lower tubes *j* is generally sufficient. Thus the cuspidor is capable of practically universal adjustment, and may be moved by its flexible supporting and

fluid-conducting standard, so as to be brought into any position convenient for the patient, who if confined to a bed may make use of the cuspidor either as a spittoon or as a urinal, by virtue of the facility afforded for bringing the upper section or supporting-arm of the standard over the bed and for moving the cuspidor itself both laterally and back and forth with respect to said section. As before stated, any pronounced angular adjustment either of the upper section of the conduit-standard or of the cuspidor will trap the discharges below, while the fresh discharges of the patient may be drained off immediately by straightening out the tubing to open the valves in the joints.

I claim as my invention and desire to secure by Letters Patent of the United States—

1. An adjustable sick-bed cuspidor comprising a base, a reservoir for discharges, and a flexible tubular supporting-standard rising from the base and carrying a mouthpiece or spittoon from which the patient's discharges are conducted through said tubular standard to said reservoir, said standard allowing a universal adjustment of said spittoon.

2. An adjustable sick-bed cuspidor having, in combination, an extensible post or standard, a tilting and swinging arm carried thereby, and a tilting spittoon or cuspidor carried by said arm also susceptible of being turned about the same, and a conduit for discharges leading from the spittoon through said arm and post.

3. An adjustable sick-bed cuspidor having, in combination, a tubular post or standard, a tilting tubular arm carried thereby and constituting a continuation of the conduit in said post, and a tilting spittoon or cuspidor carried by said arm, and having a bottom discharge opening into said arm, and provision for receiving discharges from the conduit in said arm and post.

4. An adjustable sick-bed cuspidor comprising, in combination, a base, a reservoir for discharges, a hollow extensible post or standard rising from said base, a hollow tilting and swinging arm carried by said post and communicating therewith at its joint, and a laterally and longitudinally tilting spittoon or cuspidor carried by said arm also communicating therewith at its joint, said post and arm affording a conduit for discharges from said spittoon to said reservoir.

5. An adjustable sick-bed cuspidor having, in combination, a hollow or tubular supporting-standard carrying a mouthpiece or spittoon and having an intermediate hinge-joint, said standard affording a conduit for conducting off discharges from the spittoon.

6. An adjustable sick-bed cuspidor comprising, in combination, a base-receptacle, a hollow extensible post arising therefrom consisting of a plurality of telescopically-ar-

- ranged tubes, a tilting tubular arm having a hinge-joint to the uppermost one of said tubes, which joint affords a continuing conduit therethrough, and a tube in said arm carrying a tilting cuspidor or spittoon having a similar joint with said tube. 13. A cuspidor carried by a tubular conduit having an interposed hinge-joint to permit tilting or adjustment, said joint comprising interfitted cylinders transversely affixed to contiguous ends of the pipe-sections, the outer cylinder having a circumferential cross-slot to accommodate the tube affixed to the inner cylinder and permit angular movement thereof, and the said inner cylinder having the end of its pipe-section inserted therethrough and shaped to fit against the interior walls of the outer cylinder. 65 70 75
7. An adjustable sick-bed cuspidor comprising a base having a reservoir for discharges and an extensible and flexible tubular combined supporting standard and conduit rising therefrom carrying a spittoon or cuspidor from which the discharges are conducted through said conduit to said reservoir. 14. A cuspidor comprising, in combination, a base adapted to act as a reservoir for the discharges, a hollow standard rising from said base, a spittoon-bowl carried by said standard, said standard adapted to act as a conduit for the discharges from said bowl to the base, a joint in said standard, whereby the bowl is movable to different positions, and means in the joint for automatically cutting off communication between the bowl and the base, when the bowl is moved to certain positions. 80 85
8. A cuspidor for sick-beds and the like having a tubular combined supporting standard and arm including a hinged or pivoted tilting section the joint of which affords a conduit therethrough when the tilting section is upright but cuts off communication and serves as a trap when said section is tilted at a substantial angle. 15. A cuspidor comprising, in combination, a base and a reservoir for the discharges, a hollow standard rising from said base, a spittoon-bowl carried by said standard, said standard adapted to act as a conduit for the discharges from said bowl to the reservoir, a combined joint and valve in said standard, and means whereby the communication between the bowl and reservoir is automatically cut off at said joint when the bowl is moved to a position for use, and automatically opened for discharging the contents of the bowl, when the same is moved to another definite position. 90 95 100
9. A cuspidor carried by a tubular conduit having an interposed hinge-joint to permit tilting or adjustment, said joint comprising a cylindrical casing transversely affixed to the end of one pipe-section, and a similarly-disposed cylinder having the contiguous end of the other pipe-section inserted therethrough, the latter cylinder being closely fitted in the former but susceptible of being turned therein, and the outer cylinder having a circumferential cross-slot to accommodate the tube affixed to the inner cylinder and permit angular movement thereof. 10. A cuspidor carried by and in communication with a tubular supporting-conduit having an interposed hinge-joint to permit tilting or adjustment, said joint comprising a cylindrical casing transversely affixed to the end of one pipe-section, and a similarly-disposed cylinder connected to the contiguous end of the other pipe-section and rotatably fitted in said casing and affording communication between the said pipe-sections. 11. A cuspidor carried by a tubular conduit having an intermediate hinge-joint comprising interfitted cylinders transversely affixed to contiguous ends of the pipe-sections, one of said cylinders having a catch adapted to engage a series of holes in the other cylinder for positively holding the conduit in different adjusted positions. 12. An adjustable sick-bed cuspidor comprising, in combination, a base-receptacle, a hollow extensible post arising therefrom consisting of a plurality of telescopically-arranged tubes, a tilting tubular arm having a hinge-joint to the uppermost one of said tubes, said joint comprising interfitted cylinders transversely affixed to contiguous ends of adjacent pipe-sections, and a tube telescopically fitted in said arm carrying a tilting cuspidor or spittoon having a similar joint with said tube. 13. A cuspidor comprising, in combination, a base and a reservoir for the discharges, a hollow standard rising from said base, a spittoon-bowl carried by said standard, said standard adapted to act as a conduit for the discharges from said bowl to the reservoir, two elbow-joints in said standard having a material portion of the hollow standard between the same, and means in each joint for 105 110 115 120 125

automatically cutting off and opening communication through the standard thereat, according as the spittoon-bowl and the intervening portion of the standard are moved to certain positions, whereby the said intervening portion of the standard becomes a temporary receptacle for discharges on their way from the bowl to the reservoir, and the bowl

may at all times be cut off from direct communication therewith.

In testimony whereof I affix my signature in presence of two witnesses.
